UNITED STATES PATENT OFFICE.

BENJAMIN LUKENS, OF PENDLETON, INDIANA.

FEED-CUTTER.

SPECIFICATION forming part of Letters Patent No. 367,050, dated July 26, 1887.

Application filed March 28, 1887. Serial No. 232,741. (No model.)

To all whom it may concern:

Be it known that I, BENJAMIN LUKENS, a citizen of the United States, residing at Pendleton, in the county of Madison, State of Indiana, have invented certain new and useful Improvements in Feed-Cutters, of which the following is a specification, reference being had therein to the accompanying drawings.

The object of this invention is to provide a machine for cutting or slicing ears of corn, with or without their husks, into suitable sizes for feeding purposes, and although the machine is especially adapted for this purpose, still it may be used for cutting vegetables, fruit, &c., into predetermined sizes for different purposes.

Further objects and advantages of the invention will be hereinafter specified, and the novel features thereof specifically pointed out in the claims.

Referring to the drawings, Figure 1 is a side elevation of a machine constructed in accordance with my invention. Figs. 2 and 3 are plans of the bottom and top castings, respectively, composing the base of the machine; and Fig. 4 is a sectional detail showing the points of contact of the knives or cutters and the object being cut and the means for regulating the size or thickness of the slices. Fig. 5 is a side elevation of the slice gaging and discharging devices.

Like letters of reference indicate like parts in all the figures.

In this instance the base is hollow and consists of two annular castings, A A', one mounted upon the other, and joined together by means of bolts A³, passing through binding ears or clips A², formed on the exterior of said castings. The base thus formed is mounted upon a suitable standard, Y. Mounted upon the base, at one side thereof and bolted thereto, is a yoke, B, at the upper end of which are formed bearings B' for the shaft C, having at its outer end a crank, C², and at its opposite end a bevel-gear, C³.

The castings A A' are centrally bored, as at A⁹, and through the same is passed a spindle, D, to the upper end of which is fixed a bevel-gear, D', meshing with the gear C³. A boss, D², perforated and provided with an adjusting-screw, D³, serves as a lower bearing for said spindle D, and a temper-screw, D⁴, mounted

in a curved bracket, D⁵, upon the top of the base, forms an upper adjustable bearing for said spindle.

Keyed to the spindle D, and within the annular castings A A', is a balance-wheel, E, and projecting from said wheel to the periphery of said castings is a knife, or it may be a series of knives, E'. In the path of the knife E' in the castings A A' are openings A⁴ A⁶, and at one side thereof are oppositely-arranged fixed blades A⁸. Above the opening A⁴ is a hopper, A⁵, and below the opening A⁶ is a delivery-spout, A⁷.

It will now be seen that objects to be cut or sliced may be dropped in the hopper A⁵, when, by revolving the crank C², the gear C³ will be rotated, which will impart motion to the gear D', spindle D, and balance-wheel E, carrying the knife E', whereby said knife will be brought into contact with the object to be cut, and by reason of the shear-blade of said knife E' the object will be sliced, the slices dropping through the opening A⁴ into the delivery-spout A⁷ and into any suitable receptacle placed thereunder.

By reason of the thickness of the fixed blade A⁸, slices cut from the object are prevented from being carried back of said blades into the annular castings, and thus retarding the operation of the machine.

Referring to Figs. 4 and 5 of the drawings, which are details showing devices employed for gaging the slice and delivering the same to the delivery-spout, F represents a bracket, 85 pivoted to (as at F¹) and depending from the lower casting, A', and passing through the delivery-spout A⁷, and having an aperture therein. F¹ represents a gage-rod having a slightly-concaved head at its top and provided 90 with a slot registering with the aperture in the bracket F, and adjustably connected thereto by means of a set-screw, F². A coiled spring, F³, normally retains the rod and bracket in a vertical position, and it is evident that said gage may be raised or lowered to and from the cutters thereabove, thus determining the width of the slices to be cut. Furthermore, it will be apparent that, owing to the slight concavity in the head of the rod, the corn or other article 100 resting therein, the jarring caused by the cutters coming in contact with and passing through the article being sliced will cause the bracket and the gage-rod to swing against the

tension of the spring, tilting its top or head, upon which the slice rests after the cut is made, to the front, and thus deliver the same in the spout A⁷.

5 Having described my invention and its operation, what I claim is—

1. In a feed-cutter, the combination of a hollow annular base having fixed blades, a spindle passing therethrough provided with a rotatable balance-wheel carrying a cutter, and a bevel-gear, with devices for adjusting said spindle and rotating the same, substantially as specified.

2. The combination of the castings A A', the 15 fixed opposite knives, A⁸ A⁹, the spindle D, carrying the wheel E, knife E', and gear D', with the yoke B, shaft B', gear C³, and crank C², substantially as specified.

3. The combination of the base A A', perforated, as at A⁹, with the spindle D, wheel E, 20 knife E', the bracket D⁶, temper-screw D⁴, the boss D³, and the set-screw D², substantially as specified.

4. The combination of the base A A', having openings A⁴ A⁶ and fixed knives A⁸, with the 25 bracket F, adjusting-screw F², slotted gage-rod F', and the rotating knife E', substantially as specified.

In testimony whereof I affix my signature in presence of two witnesses.

BENJAMIN LUKENS.
